LIGHTING DEVICE FOR SEWING MACHINES

Wilbur J. Peets, Watchung, and Anthony J. Matuzas, Union, N. J., assignors to The Singer Manufacturing Company, Elizabeth, N. J., a corporation of New Jersey

Application April 28, 1951; Serial No. 223,488

3 Claims. (Cl. 240—2.14)

1

This invention relates to a sewing machine and more particularly to a lighting device for a sewing machine.

An object of the invention is to provide a light for a sewing machine which will adequately light the stitching area of the sewing machine.

Another object of the invention is to provide a sewing machine light which will concentrate beams of light at the stitching area of the sewing machine.

A further object of the invention is to provide a sewing machine light with a reflector and lens which are readily removable for bulb replacement and servicing.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a front elevation of a sewing machine embodying the invention.

Fig. 2 is a fragmentary front elevation, partly in section, of the lighting device and sewing machine.

Fig. 3 is a sectional view of the sewing machine bracket-arm and lighting device taken on line 3—3 of Fig. 1.

Fig. 4 is a partial sectional view of the sewing machine bracket-arm and lighting device taken on line 4—4 of Fig. 1.

Fig. 5 is a partial sectional view of the sewing machine bracket-arm and lighting device taken on line 5—5 of Fig. 1.

Fig. 6 is a rear perspective view of the lighting device reflector and lens.

Referring more specifically to the drawings, the invention is disclosed as being embodied in a sewing machine having a bed 10. A bracket-arm 11 having a standard mounted on and rising from the bed 10, is provided with a hollow horizontal portion which terminates at its free end in a head 12. A needle 13 is carried by a needle-bar 14 mounted in the head 12. The needle 13 passes through a hole in the usual throat-plate 15 mounted on a cloth-plate 16. A balance-wheel 17 is attached to one end of a rotary actuating shaft 18 journaled in and extending longitudinally of the bracket-arm. A bobbin-winder support arm 19 is pivotally connected to the bracket-arm 11 by a pivot stud 20. The support arm 19 carries a bobbin spindle 21 which is driven

2

by a friction wheel 22 fastened to one end of the spindle 21. The friction wheel 22 may be manually pressed against a hub portion 23 of the balance-wheel by means of a handle 24 integral with and forming an extension of the support arm 19.

The bracket-arm 11 is formed in the front wall thereof with a recess 25 to receive a lighting unit 27 which comprises a lamp-socket and switch 28 and an electric-light bulb 29. The lighting unit 27 is attached to the bracket-arm by means of a clamp 30 which encircles the lamp socket and is fastened to the bracket-arm by a screw 31. A switch operating knob 32 is positioned to be readily accessible at the under side of the lamp and an electrical conductor 33 is attached to the socket 28 and to a suitable electric power source (not shown). A light-reflector 34 is fastened to the front wall of the bracket-arm 11 by screws 35 and 36. The inner or reflecting surface of the reflector 34 is formed with a support groove 37 extending along one end and approximately one-half the length of the reflector. A similar and horizontally opposed support groove 38 is formed in the bracket-arm around one end of the recess 25.

A lens 39 is formed with a light focusing portion 40 and a support lip or flange 41. One portion of the lip 41 is positioned in the support groove 37 in the reflector 34. The lens is fastened to the reflector by a clamp 42 which is positioned over the inner edge of the lens lip portion and fastened to the reflector by a screw 43. The reflector and lens assembly is positioned against the bracket-arm with the bracket-arm support groove 38 receiving the remaining portion of the lip 41. The screws 35 and 36 are inserted through suitable holes 44 and 45, respectively, in the reflector and are threaded into holes 46 and 47, respectively, in the bracket-arm to hold the reflector and lens in place. It should be noted that the lens 39 extends beneath the bulb 29 and a small portion of the socket 28 but does not interfere with the switch operating knob 32.

From the foregoing description, the advantages of my invention will be readily apparent. In assembling the lighting device, the lighting unit 27 comprising the socket 28 and bulb 29 is attached to the bracket-arm by means of the clamp 30 and the screw 31. The lens 39 is positioned on the reflector 34 with the groove 37 receiving a portion of the lens lip 41. The lens clamp 42 is fastened to the reflector by the screw 43 to hold the lens in place on the reflector. The

lens and reflector assembly is easily positioned on the bracket-arm with the remaining portion of the lens lip 41 positioned in the bracket-arm groove 38 and the fastening screws 35 and 36 are then threaded into place. Thus, in assembling the device the complete lens and reflector assembly is easily attached to the bracket-arm. There is no lens to be handled individually with the resulting high percentage of breakage. Similarly, when it is necessary to replace a broken or burned out bulb or service the socket 28, it is only necessary to remove the two attaching screws 35 and 36 and remove the reflector and lens assembly as a unit. The bulb and socket are then readily accessible and the bulb may be easily replaced or the socket may be serviced. After the necessary servicing has been done, the lens and reflector assembly is again positioned on the bracket-arm with a portion of the lens lip 41 in the bracket-arm groove 38 and the reflector attaching screws 35 and 36 are threaded into place. Throughout the servicing operations, the lens and reflector are handled as an assembly which, when removed, completely exposes the light bulb 29 and the socket 28. When the lighting device is completely assembled, as shown in Fig. 1, the lens 39 permits light from the bulb 29 to be evenly distributed over the cloth-plate 16 except for the area of the throat-plate 15. The focusing portion 40 of the lens concentrates beams of light at the stitching area to brightly illuminate that area. Thus the entire area of the cloth-plate is evenly and adequately lighted while the stitching area is brilliantly lighted by the concentrated beam of light. Thus I have provided a lighting device which provides adequate lighting over the entire cloth plate; provides brilliant illumination at the throat-plate; is easily assembled; and the reflector and lens of which can be removed as an assembled unit for easy access to the light bulb and its socket.

Having thus set forth the nature of our invention, what we claim herein is:

1. In a sewing machine having a frame including a bracket-arm provided in its front wall with a clearance recess and with a groove, both extending lengthwise of said bracket-arm, a light unit having a portion thereof disposed in said recess and secured to said bracket-arm, a re-

flector-unit comprising a segmental reflector-element internally provided with a groove extending lengthwise of said reflector-element, a lens having oppositely directed side flanges, and means for securing said lens to said reflector-element with one of the side flanges of said lens seated in the reflector-element groove, and means for securing said reflector-element to said bracket-arm with the other side flange of said lens seated in the groove of said bracket-arm.

2. A sewing machine having a bed, a bracket-arm carried by said bed and terminating in a head, said bracket-arm having a recess and a lens supporting groove formed in its front wall, a lighting unit carried by said bracket-arm in said recess, said lighting unit having a switch control and a light source, a light reflector positioned over said lighting unit and having a support groove formed in its reflecting surface, a lens positioned in said grooves and removably fastened to said reflector, said lens extending under said light source only, and removable fastening means securing said reflector to said bracket-arm and accessible when said lens is secured to said reflector.

3. A sewing machine having a bed, a bracket-arm carried by said bed and terminating in a head, said bracket-arm having a recess and a lens-supporting groove formed in the bracket-arm, a lighting unit comprising a light source and a light switch carried by said frame in said recess, a light reflector positioned over said lighting unit and provided with a lens-supporting groove in its reflecting surface, a lens positioned in said grooves, a single clamp and clamp-screw securing said lens to said reflector, said lens extending under said light source only, and removable fastening means securing said reflector to said bracket-arm and accessible when said lens is secured to said reflector.
